United States Patent Office

Des. 195,858
Patented Aug. 6, 1963

195,858

COIN BANK

Marvin Hoffman, 22900 Recreation,
St. Clair Shores, Mich.

Filed June 18, 1962, Ser. No. 70,588

Term of patent 14 years

(Cl. D34—11)

Fig. 1

Fig. 2

Fig. 3

Fig. 4

FIG. 1 is a front elevational view of a coin bank which embodies my new design;

FIG. 2 is a side elevational view thereof, the side opposite (not shown) being a mirror image thereof;

FIG. 3 is a plan view; and

FIG. 4 is a perspective view thereof.

The essential features of my design reside in those portions shown in the drawing in full lines.

I claim:

The ornamental design for a coin bank, as shown and described.
